UNITED STATES PATENT OFFICE.

EDWARD C. POST, OF CHICAGO, ILLINOIS, ASSIGNOR TO VAPOR CAR HEATING COMPANY, INC., OF CHICAGO, ILLINOIS, A CORPORATION OF ILLINOIS.

COUPLER.

Original application filed March 9, 1922, Serial No. 542,297. Divided and this application filed April 18, 1924. Serial No. 707,379.

To all whom it may concern:

Be it known that I, EDWARD C. POST, a citizen of the United States, residing at Chicago, in the county of Cook and State of Illinois, have invented certain new and useful Improvements in Couplers, of which the following is a specification.

My invention relates to a hose coupling, especially a coupling intended for detachably uniting the hoses or equivalent flexible, metal, tubular elements on the ends of the train pipes of adjacent cars of a railroad train.

The primary object of my invention is to provide a novel, simple coupling of economical construction of which the mating couplers may be brought into a preliminary engagement by a lateral movement of one member toward the other (without the usual rocking or angular movements characteristic of the gravity type of coupling) and then drawn into fluid tight relation with their gaskets pressed one against the other to complete the coupling operation. More specifically, my invention contemplates the formation of one of the elements of the coupling with a projecting lug and the other with a sliding member which is forced into engagement with said lug, so as to draw the couplers. The term "coupler" is used to denote one of these members. The coupling may consist of two members, each constructed in accordance with my present invention, but a single coupler as constructed may be mated with another coupler differently designed so long as the other coupler is provided with engaging parts of suitable configuration and properly placed to effect an interlocking engagement with the corresponding part of the other coupler.

The invention consists in the new and improved constructions, arrangements and devices to be hereinafter described and claimed for carrying out the above stated objects, and such other incidental objects as will appear from the following description of a preferred embodiment of the invention as shown in the accompanying drawing.

In the drawing:

Fig. 1 is a plan view, with certain parts in

section, of a coupling of two identical couplers made in accordance with my invention.

Fig. 2 is a side elevation of the coupling shown in Fig. 1.

Fig. 3 is a view, in perspective, of the sliding member employed in the construction of the invention shown in Figs. 1 and 2.

Fig. 4 is a fragmentary view in elevation of the sliding member showing the other side of the same from that shown in Fig. 3, and

Fig. 5 is a view in perspective of the actuating cam for moving the sliding member of a coupler into locking engagement with another coupler as shown in Figs. 1 and 2.

In the drawing I have shown my improved coupling made up of two, preferably though not necessarily, identical couplers A and B. Each of these couplers consists of a head 10 provided with the usual fluid passage therethrough and with a gasket 11 of suitable construction fitted in the end of such fluid passage so as to bear against a corresponding gasket of the mating coupler when said coupling is in its assembled operative position. The coupler heads are each formed on one side with an undercut lug 12 and on the other side with a forwardly projecting arm 13 having outstanding parallel flanges 14, 15 between which is arranged a sliding member 16. This member is provided at its forward end with a head 17 projecting through an opening 18 in the arm and formed with an undercut curved lug 19 adapted to engage the lug 12 on the mating coupler. The rear portion of member 16 is formed with a recess 20 and with upper and lower slots 21, 22. The sliding member 16 is actuated by means of a rotary cam or eccentric 23 arranged in recess 20 of the sliding member and held in place by means of a stud 24 which is fixed by cotter pin 25 in the flanges 14, 15 and extends through slots 21, 22 in the member 16 and through a perforation 26 in the cam 23. The cam is provided with a suitable handle 27 and to allow the necessary amplitude of movement to the cam the back wall 28 of the sliding member 16 is cut away as indicated at 29 and the side of said member is grooved out, as indicated at 30. The cam 23 is adapted to bear against the back wall

100
105

28 of the member 16 and against the surface 31 thereof defining the recess 20 at its forward side.

The sliding member 16 is applied in its operative position by inserting the recessed end 32 through the opening 18 of the arm 13 so that the flat surface 33 of the end 32 will slide along on the flat surface 34 of the side of the coupler, the inner face 35 held in sliding engagement with the surface 36 of the coupler and the outer faces 37-37 of the lug 17 held in sliding engagement with the inner face of the arm 13 so as to prevent any appreciable angular or lateral displacement 15 of the sliding member.

Operation: When connecting the couplers, the handles 27 of the rotary cams of both couplers, when both couplers are of the type shown, are turned toward the outer ends of 20 the arms 13. Such movement of the cams moves the sliding members 16-16 outwardly toward the end of the arms 13-13 and thereby permits a preliminary engagement of the couplers to be effected by moving one 25 toward the other sidewise. After the preliminary engagement is made the cams are rotated, as far as necessary, in the opposite direction to bring the gaskets 11-11 of the couplers into intimate contact. The curved 30 surfaces of the lugs 12-12 and that of the co-engaging lugs 19-19 are such as to automatically align the center of the couplers when one of said curved surfaces is forced 35 against another, thereby ensuring that the coengaging faces of the gasket 11-11 will bear flatwise against the other. The movement of the sliding member 16 is positive in both directions.

While I have described my invention in 40 one specific embodiment, it is obvious that modifications in structure might be made without departure from the principle of the invention. Therefore I wish it to be understood that the invention is not to be considered as limited to the particular constructions, arrangements and devices shown and described except so far as the claims hereto appended are specifically so limited.

This is a division of my copending application Serial No. 542,297 filed March 9, 1922, now Patent No. 1,508,408 dated September 16, 1924.

I claim:

1. A coupler for use as an element of a 55 hose coupling, comprising a head formed with a port therethrough, a lug on one side of said head, an arm forwardly projecting from the other side and formed with guide flanges, a member slidible between said 60 guide flanges and adapted to engage the mating coupler, and formed with outstanding slotted webs, a pivot pin extending through said flanges and through the slots in said web, a rotary eccentric on said pivot 65 pin engaging said member to move the same

back and forth, and a handle on said eccentric.

2. For use as an element of a hose coupling, a coupler head provided with a forwardly extending arm, a member slidible on 70 said arm and adapted to be engaged with a mating coupler by a lateral movement of said couplers, and means comprising a cam supported to rotate on an axis transversely of the length of said coupler to actuate said 75 sliding member to draw the couplers together.

3. For use as an element of a hose coupling, a coupler provided with a forwardly 80 extending arm, a member slidible on said arm and adapted to be engaged with a mating coupler by a lateral movement of 85 said couplers, and means for actuating said slidible member to draw the couplers together comprising an element pivoted on the coupler to move longitudinally thereof.

4. A hose coupling comprising two coupler heads one of which is formed with a lug and the other with an arm having a slidible member thereon adapted to be engaged with 90 said lug by a lateral movement of said coupler heads, and provided with an eccentric to actuate said sliding member to draw said coupler heads together.

5. A hose coupling comprising two coupler heads, one of which is formed with a lug and the other with an arm having a slidible member thereon adapted to be brought into 100 preliminary engagement with said lug by a lateral movement of said heads and provided with an eccentric pivoted to move longitudinally of said last mentioned coupler to actuate said slidible member.

6. A hose coupling comprising coengaging coupler heads adapted to be moved into preliminary engagement with each other by a lateral movement, each of which is formed on one side with an undercut lug and provided on the other side with an arm having a slidible member thereon formed with an 110 undercut portion for engaging the undercut lug of the mating coupler, and provided with a rotatable eccentric for actuating said slidible member.

7. A coupler for use as an element of a 115 hose coupling, comprising a head formed with a port therethrough, a lug on one side of the head, an arm forwardly projecting from the other side, a member slidible on 120 said arm and adapted to engage with a mating coupler, and means for actuating said slidible member to draw the couplers together comprising a member pivoted to rotate longitudinally of said coupler.

8. A coupler for use as an element of a 125 hose coupling, comprising a head formed with a port therethrough, a lug on one side of the head, an arm forwardly projecting from the other side, and a member slidible 130 on said arm and provided at one end with a

lug for engaging the mating coupler and at the other end with a recess, and a rotary eccentric positioned in said recess and adapted when rotated to impart movement to said slidible member.

9. A coupler for use as an element of a hose coupling, comprising a head formed with a port therethrough, a lug on one side of the head, an arm forwardly projecting from the other side and formed with guide

flanges, a member slidible between said guide flanges and formed at one end with a lug for engaging the mating coupler and at the other end with a recess, a pivot pin extending through said flanges, and a rotary eccentric on said pivot pin and extending into said recesses to move the slidible member back and forth.

EDWARD C. POST.
